UNITED STATES PATENT OFFICE.

ARTHUR E. WHEELER, OF LOGANSPORT, INDIANA.

COMBINED RADIO LOUD SPEAKER AND LAMP.

Application filed June 30, 1925. Serial No. 40,573.

This invention relates to a combined radio loud speaker and lamp.

An important object of the invention is to provide a device of this character which ⁵ hides from view the awkward and top heavy appearance of the ordinary regular loud speaker horn and within which the radio loud speaker may be readily inserted.

A further object of the invention is to provide a device of this character which may ¹⁰ be very readily and cheaply constructed and at the same time be neat in appearance and durable in service.

These and other objects I attain by the ¹⁵ construction shown in the accompanying drawings, wherein for the purpose of illustration is shown a preferred embodiment of my invention and wherein:

Figure 1 is a side elevation of a combined ²⁰ loud speaker and lamp constructed in accordance with my invention;

Figure 2 is a vertical sectional view there-
through.

Referring now more particularly to the ²⁵ drawings, in the production of the combined unit, I provide a rectangular cabinet 10 comprising top and side walls 11 and 12 secured to one another and a removable bottom structure 13 preferably of greater size ³⁰ than the casing and socketed, as at 14, to receive the casing in its upper face. The lower edge of one side wall of the casing is formed with a notch 15 of greater depth than the socket 14 of the base for a purpose ³⁵ presently to appear. The opposite side wall of the casing is provided with a plurality of openings 16 grouped within a space corresponding to the shaping of the bell 17 of the loud speaker horn 18 which is to be employed. The inner face of this wall is ⁴⁰ preferably covered with a thin covering of silk or muslin, indicated at 19.

The loud speaker employed may be of that type having the loud speaker unit 20 thereof rigidly secured to the horn and in the top of the rectangular casing 10 which forms a base for the completed unit, an opening 21 is formed of greater size than the loud speaker unit. An upwardly tapering neck structure 22 is provided having its

lower end of greater diameter than the opening 21 so that it may rest upon the upper surface of the casing 10 about this opening and conceal the same. The upper end of this neck is reduced so that it is but ⁵⁵ slightly greater in internal diameter than the diameter of the loud speaker unit 20 which is employed and has engaged therewith a metallic cap 23. Axially of the upper wall of this cap, a stud 24 is threaded there- ⁶⁰ through and this threaded stud projects sufficiently on the under surface of this wall to enable the same to be engaged with the base 25 of the loud speaker unit so that the loud speaker unit is supported. The upper ⁶⁵ end of this stud has a threaded ornamental nut 26 adapted to hold in position a lamp-shade 27, which shade has preferably coiled therein a radio receiving loop 28. The metallic cap has secured thereto a plurality of ⁷⁰ outlets 29, each supporting a socket 30 for an illuminating element 31.

In assembling the device, the loud speaker is entered through the open bottom of the casing 10 to which the device has not yet ⁷⁵ been applied and the units thereof projected through the opening 21. The neck 22 is then placed in position over the unit and finally the cap 23 applied and secured to the unit. The cords 32, 33 of the loud speaker ⁸⁰ unit and sockets are drawn through the bottom and placed within the notch 15 and the base then applied. When the cap is secured to the loud speaker unit, the bell 17 of the loud speaker is held in opposition to the openings 16, as illustrated. The lamp-shade is then placed in position and secured by means of the nut 26. It will be obvious that since the unit may be very readily assembled and will provide for the loud speaker a ⁸⁵ steady support hiding the unsightly top heavy appearance thereof and without in any manner interfering with its proper operation. It will also be obvious that the construction hereinbefore set forth is capable of a certain range of change and modification without materially departing from the spirit of the invention and I accordingly do not limit myself to such specific structure except as hereinafter claimed. ⁹⁰

I claim:—

In combination with a radio loud speaker embodying the usual bell and loud speaker unit, a casing for the reception of the bell having an open bottom through which the bell may be inserted and having in its top wall an opening of a diameter permitting passage of the unit and the neck of the bell, a housing neck engageable over the loud speaker unit and having its lower end of a

size larger than the upper wall of the cabinet and a cap engaged with the upper end of the housing neck having means for engaging the loud speaker unit to support the same with the mouth of the bell in engagement with one wall of the casing, said wall of the casing having perforations. 15

In testimony whereof I hereunto affix my signature.

ARTHUR E. WHEELER.
